CAR COUPLER SUPPORT AND POSITIONING DEVICE

Karl T. Nystrom, Chicago, Ill., and Alfred L. Thompson, Munster, Ind., assignors to Standard Railway Equipment Manufacturing Company, Chicago, Ill., a corporation of Delaware

Application June 1, 1948, Serial No. 30,436

17 Claims. (Cl. 213—61)

1

This application is a continuation-in-part of application Serial No. 760,212, filed July 11, 1947, now abandoned, relating generally to railway cars and specifically to means for adjustably and resiliently supporting the outer end of a railway car coupler adjacent its head.

Railway cars are ordinarily equipped with striking castings which generally are of hollow rectangular shape and fixedly secured to the end of the center sill of the car. The shank of the car coupler projects within this striking casting and is secured thereto by a large pin so as to permit the required vertical and lateral angling of the coupler head. In some installations coupler centering devices are associated with striking castings, so that when cars are uncoupled, said centering device will return the coupler to a position known as "within coupling range." A great many of these centering devices are also provided with resilient means to support the coupler.

As is well known, couplers must move longitudinally, laterally and vertically within minimum limits prescribed by the Association of American Railroads, and these constant movements cause considerable wear on the under surface of the coupler shank as well as the wearing surface of the centering device supporting the same. Also if the resilient means for supporting the coupler is a spring, said springs, through usage, become weakened, and thus do not maintain the coupler at its required vertical height.

It is, therefore, the principal object of our invention to provide a coupler centering device having a single means of adjustable association with a striking casting whereby the level of the coupler supporting surface of the centering device may be readily varied to compensate for such wear or failure of other parts of the device.

It is a further object of the invention to provide a means accomplishing coupler height adjustment for couplers provided with centering devices of the spring, swing link or other types.

Other objects and advantages of the invention will appear in the following description thereof.

Referring now to the accompanying drawings forming part of this application and wherein like characters indicate like parts.

Figure 1 is a front elevation showing a typical installation of our device to a railway car.

2

Figure 2 is a side elevation of Figure 1.

Figure 3 is a section on line 3—3 of Figure 1.

Figure 4 is a section on line 4—4 of Figure 1.

Figure 5 is a partial front elevation similar to Figure 1 of a modified form of the invention.

Figure 6 is a section on line 6—6 of Figure 5.

Figure 7 is a front elevation of a coupler support and positioning device of the swing link type having associated therewith a modification

of our invention.

Figure 8 is a perspective view of the rotatable trunnion pocket or bearing block for supporting the links of the modification shown in Figure 7.

Figure 9 is a central vertical section on line 9—9 of Figure 7.

Figures 10, 11 and 12 are partial front elevations—one side of the striker illustrating successive positions of the trunnion bearing block therein.

20 In the form of the invention shown in Figures 1 to 4, the striking casting is shown generally at 2, which is customarily attached to the center sill of the car by means of rivets extending through holes 3 to thereby hold same to the car underframe. The car coupler shank is indicated in dotted lines at 4 as resting upon the carrier 6 between the spaced walls 9 and 10 of the striking casting which restricts movement of the carrier longitudinally of the car but permits vertical reciprocation thereof. Walls 9 and 10 also provide an emergency support for the coupler in case of breakage or loss of any of the parts of the device. Spaced springs 12 extend between carrier 6 and rocker 20 resting on bottom wall

25 13 of centering device and thus provide a resilient support for the coupler. As the coupler moves laterally it takes the carrier 6 therewith causing the springs to tilt and distort somewhat, and the rocker to rock, thereby providing a re-

30 35 storing moment to return the coupler to coupling range when free to do so. Bottom 13 of the centering device extends between the central portions of the spaced walls 21 and 22, the lower outer corners of which are provided with registering holes which register with elongated holes

35 40 45 23 through walls 9 and 10 for application therethrough of pins 24 thereby holding the centering device within the striking casting. Upon each pin 24 between walls 21 and 22 is a solid poly-

verse hole therethrough through which the pin 24 passes, and it will be noted from Figure 1 that the axis of the pin is at a different distance from each side of the block. As one wall of the block 25 rests upon the walls 26 of the striking casting, a ninety degree rotation of the block on pin 23 will present another face thereof to rest upon the wall 26 and thus accordingly raise or lower, as the case may be, the coupler support in relation to the striking casting, which, of course, will correspondingly move the coupler. While we have shown the block 25 as rectangular, thereby providing four manually adjustable positions of the coupler support, it is obvious that a hexagonally or octagonally shaped block may be used to provide more adjustable positions, if such were necessary.

In the modified form of the invention illustrated in Figures 5 and 6 the structure of the coupler support and positioning device and that of the striking casting are the same as in the formerly described modification, the only difference being in the location of the means for adjusting the position of the support and positioning device in relation to the striking casting.

Corresponding parts of the two modifications which are identical in structure are indicated by the same reference characters, so that the description thereof need not be repeated.

In this modified form, the wall 26 of the striking casting is provided with a pair of spaced rectangular openings therein, so that one wall of the rotatable blocks 31 may project therethrough. Two pairs of aligned spaced holes are provided through the lower part of the walls 9 and 10 of the striking casting for reception of the pins 31 which also project through holes in the blocks 30 and maintain the same in position between said walls. Rocker support 32 rests upon the upper surface of walls of blocks 30, which in turn supports the rocker 20, the springs 12 and coupler carrier 6 upon which coupler shank rests. Inner and outer walls 21 and 22 of carrier are riveted to the striking casting by means of rivets 33. Thus by rotating the blocks 30 the rocker support 32 may be raised or lowered accordingly and thereby vary the height of the coupler in relation of the striking casting.

In Figures 7 to 12 inclusive the invention is shown as applied to a coupler carrier suspended by swinging links, such as illustrated in Patent No. 1,944,422 of January 23, 1934, owned by our assignee, and the invention herein constitutes an improvement over the trunnion bearing block shown and described in said patent. In these figures of the drawing, the usual car parts are indicated, such as the striking casting 40, coupler 41, coupler carrier 42 having upstanding lugs 43 to retain the coupler 41 centrally thereupon, and bifurcated or forked end portions each having an inverted bearing for a trunnion, and links 44, each having trunnions 45-45 at each end thereof. Striking casting 40 is provided with opposed integral lugs 46-46 which extend toward each other from the front 47 and rear 48 walls of the striking casting, but are spaced from each other so that the shank of link 44 may swing therebetween. These lugs provide a supporting ledge for the rotatable trunnion bearing block 49 for the carrier supporting trunnioned links 44.

The rotatable trunnion bearing block 49 is formed as an integral casting and comprises a pair of walls 50-50 which are spaced apart parallelly a distance about the width of the shank of link 44, and with a hollow semi-cylindrical

connecting arm 51. A hole 52 extends through walls 50-50 and registers with the hollow surface 51' of arm 51 when in the position shown in Figure 7, and registering tapering holes forming trunnion bearings 53 are provided through walls 50-50, approximately axially thereof. In side elevation (see left of Figure 7) the sides 50 of trunnion bearing block are generally circular, but provided with four flat facets 54, 55, 56 and 57, which are designed to selectively rest upon the lugs 46-46. These facets are arranged on the periphery of the trunnion bearing so as to be at progressively increasing distances from the axis of bearings 53, the facets 54 being spaced the shortest distance from said axis, and facet 57 being spaced the longest distance therefrom. When the trunnion bearing is placed in position in striker 40 with facets 54 resting on lugs 46, registering holes 58 in front and rear surfaces 47 and 48 of striker will also register with holes 52 and surface 51' and consequently a large cotter pin 59 may pass therethrough and hold the trunnion bearing in that position. In this position with upper trunnions 45-45 in trunnion bearings 53, and lower trunnions swingingly supporting the coupler carrier 42, which in turn supports the coupler, the coupler is supported in normal position.

It will be noted that there are three semi-circularly shaped notches 60, 61 and 62 in the periphery of each wall 50, which, together with holes 52, are equally spaced apart. Thus when any of the moving parts wear, the amount of wear will cause a lowering of the coupler height, and to compensate for this, cotter pin 59 is removed, and rotatable trunnion bearing block 49, rotated until the next facets 55 rest upon lugs or ledges 46, at which time holes 58 will register with notch 60 (see Figure 10) and the coupler will then be raised because of the increased distance between facets 55 and axis of bearings 53. If further adjustment of the coupler height is necessary, this process of rotating the trunnion bearing can be repeated, as shown Figure 11, and to a final position, as shown in Figure 12, to provide the maximum coupler height adjustment.

To prevent the facet of the block 49 from sliding on the lugs or ledges 46, a rectangular shaped protrusion 64 is integrally formed on ledges 46-46 at junctures thereof with front 47 and rear 48 walls of the striker. Correspondingly shaped notches 65 are formed in trunnion bearing block to selectively register with protrusion 64 and consequently, when cotter 59 is in place, the block cannot move.

For convenience in assembling the trunnion bearing block 49 in the striker with the same facet of each resting on its respective facet, rectangular openings 70 are provided through the front wall 47 of the striker, through which may be seen either of the numerals 1, 2, 3 or 4 cast in the side of the bearing blocks 49, as clearly seen in Figures 7 and 8. Thus when an adjustment in coupler height is made, the same numeral should appear through said openings on both sides of the striker which indicates at a glance that the corresponding facets of each block are resting upon ledges 46.

It will be noted in Figure 8 that the inner surface of walls 50-50 diverge outwardly from bearings 53 in the area of the semi-circular notches 60, 61 and 62. This is for convenience in applying the trunnioned link into said bearing.

The accompanying drawings illustrate the pre-

ferred form of the invention, though it is to be understood that the invention is not limited to the exact details of construction shown and described, as it is obvious that various modifications thereof, within the scope of the claims, will occur to persons skilled in the art.

We claim:

1. A railway car coupler carrier mechanism comprising a coupler carrier adapted to support a coupler shank, an adjustable support, means extending between said support and said carrier to support said carrier, and means including an eccentric rotatable block between said support and a car part for varying the relation of said support to said car part to thereby optionally vary the elevation of a coupler carried by said carrier upon rotation of said block.

2. A railway car coupler carrier mechanism comprising a coupled carrier adapted to support a coupler shank, an adjustable support, means extending between said support and said carrier to support said carrier, and an eccentrically mounted rotatable polygonal block for varying the elevation of said support to thereby optionally vary the elevation of a coupler carried by said carrier.

3. A railway car coupler carrier mechanism comprising a coupler carrier for supporting a coupler, means for supporting said carrier, adjustable means for supporting said means, and a polygonally shaped eccentrically mounted rotatable block for adjusting said adjustable means to vary the elevation of said carrier.

4. A railway car coupler carrier mechanism comprising a coupler carrier having end portions adapted to support therebetween a coupler shank, and a polygonally shaped block eccentrically and rotatably arranged below said carrier upon a car part for supporting said carrier in optionally varying relation to said car part.

5. A railway car coupler carrier mechanism comprising a coupler carrier having end portions adapted to support therebetween a coupler shank, a laterally movable support for said end portions, and a polygonally shaped block eccentrically and rotatably arranged upon a car part to selectively vary the elevation of said carrier.

6. A railway car coupler carrier mechanism comprising a coupler carrier having end portions adapted to support therebetween a coupler shank, a laterally movable trunnioned support for said end portions, and a polygonally shaped block eccentrically and rotatably arranged upon a car part and associated with said support and provided with trunnion bearings for the trunnions of said support to selectively vary the elevation of said carrier.

7. A coupler carrier mechanism for a railway car having a striker provided with opposed integral ledges, said mechanism including a rotatable eccentric trunnion bearing block having a plurality of facets adapted to selectively rest upon said ledges, said block having a trunnion bearing therein, a coupler carrier having end portions provided with trunnion bearings, and a link having trunnions at each end for application to the bearings of said block and carrier.

8. A coupler carrier mechanism for a railway car having a striker provided with opposed integral ledges, said mechanism including a rotatable eccentric trunnion bearing block having spaced sides each having a plurality of facets

adapted to selectively rest upon said ledges, said sides having a trunnion bearing therein, a coupler carrier having bifurcated end portions provided with inverted trunnion bearings, and a link having trunnions at each end for application to the bearings of said block and carrier.

9. A coupler carrier mechanism for a railway car having a striker provided with opposed integral ledges and integral protrusions on said ledges, said mechanism including a rotatable eccentric trunnion bearing block having a plurality of facets adapted to selectively rest upon said ledges, each facet having a notch therein, said block having a trunnion bearing therein, a coupler carrier having end portions provided with trunnion bearings, and a link having trunnions at each end for application to the bearings of said block and carrier, said notches registerable with said protrusions to maintain said block in any selected position.

10. A rotatable trunnion bearing block having a plurality of peripheral facets, and a plurality of semi-cylindrical peripheral notches substantially opposite said facets.

11. A rotatable trunnion bearing block having spaced sides each having a plurality of peripheral facets, each facet having a notch therein, and a plurality of semi-cylindrical peripheral notches substantially opposite said facets.

12. A rotatable trunnion bearing block having spaced sides each having a plurality of peripheral facets, each facet having a notch therein, aligned openings through said sides forming a trunnion bearing, and a plurality of semi-cylindrical peripheral notches substantially opposite said facets.

13. A railway car coupler carrier mechanism comprising a coupler carrier having end portions adapted to support therebetween a coupler shank, a laterally movable support for said end portions, and a block having facets at varying distances from the axis of the block eccentrically and rotatably arranged upon a car part between said shank and said support to selectively vary the elevation of said carrier upon rotation of said block.

14. A coupler carrier mechanism for a railway car having a striker, said mechanism comprising a coupler carrier adapted to support a coupler shank, a pair of eccentric rotatable blocks rotatably supported in said striker, and means between the carrier and the blocks for supporting the carrier, whereby rotation of said blocks will vary the elevation of said carrier.

15. A coupler carrier mechanism for a railway car having a striker, said mechanism comprising a coupler carrier adapted to support a coupler shank, a pair of eccentric rotatable blocks, means for rotatably supporting said blocks in said striker, and means between the carrier and the blocks for supporting the carrier, whereby by rotation of said blocks will vary the elevation of said carrier.

16. A coupler carrier mechanism for a railway car having a striker, said mechanism comprising a coupler carrier adapted to support a coupler shank, a pair of eccentric rotatable blocks, each having a plurality of facets, means for rotatably supporting said blocks in said striker, and means between the carrier and the blocks for supporting the carrier, whereby by rotation of said blocks corresponding selected facets may be brought into position to elevate said carrier a predetermined amount through said last mentioned means.

7
 17. A coupler carrier mechanism for a railway car having a striker provided with integral ledges, said mechanism including a pair of eccentric rotatable blocks, each having a plurality of facets adapted to selectively rest upon a ledge, a coupler carrier adapted to support a coupler shank, and means between the carrier and the blocks for supporting the carrier, whereby rotation of said blocks will vary the elevation of said carrier.
